AIR CONDITIONING SYSTEM

Alwin B. Newton, Minneapolis, Minn., assignor to
Minneapolis-Honeywell Regulator Company,
Minneapolis, Minn., a corporation of Delaware

Application July 26, 1939, Serial No. 286,594

14 Claims. (Cl. 62—8)

This invention relates to an air conditioning system and more particularly to a system of the type shown and described in my copending application Serial No. 243,843, filed December 3, 1938.

In this earlier application, a method of controlling the thermostatic expansion valve of a refrigeration system to vary the cooling capacity thereof is disclosed. The method consists in providing connections between the operating bellows or diaphragm of the expansion valve and the inlet and outlet portions of the evaporator, and controlling the relative effectiveness of the connections so that the operating bellows or diaphragm of the valve may respond to the pressure at the evaporator inlet or at the evaporator outlet, or to some intermediate pressure, and in this manner the cooling capacity of the evaporator may be readily adjusted in accordance with some condition to be controlled, such as the temperature of a space. The reason why the capacity of an evaporator may be controlled in this manner is because of the drop in pressure through the evaporator, so that if the operating member for the expansion valve responds to the relatively low pressure at the evaporator outlet, a smaller rise in temperature is necessary to cause the valve to open than when the operating member responds to the higher pressure at the evaporator inlet, so that, for a given evaporator pressure, if the valve operating bellows or diaphragm responds to the higher inlet pressure, the valve will not open until the temperature at the evaporator outlet rises to a higher value than when the valve operating bellows or diaphragm responds to the lower pressure existing at the evaporator outlet. Accordingly, a greater portion of the evaporator will contain superheated refrigerant when the pressure connection is taken at the evaporator inlet than when it is taken at the evaporator outlet. Therefore, by varying the relative effectiveness of the two pressure connections, different portions of the evaporator will contain superheated refrigerant, and the effective cooling area of the evaporator may be readily controlled.

While the system of this copending application is entirely satisfactory in many applications, it may not be suitable where the pressure drop through the evaporator coil is relatively small, since the success of the system shown in this copending application is dependent upon the existence of a substantial pressure drop through the evaporator coil. Furthermore, in this earlier system, modulation of the evaporator coil is usually limited between 100% of coil capacity and about 60% of coil capacity. In many applications, it is desirable to modulate the evaporator coil between 100% and 0% coil capacity.

In accordance with the teachings of the present invention, it is possible to modulate the coil from 0% to 100% coil capacity, even in those cases where the pressure drop through the evaporator is relatively small.

It is accordingly an object of the present invention to provide a novel arrangement for controlling the effective cooling surface of an evaporator coil of a direct expansion refrigeration system.

More specifically, it is an object of the present invention to provide a novel arrangement for modulating the capacity of an evaporator coil of a direct expansion refrigeration system between 100% and 0%.

Another object of the present invention is the provision of a self contained valve and operating means therefor to be applied to the equalizer connection between the expansion valve and evaporator coil of a direct expansion refrigeration system or in some other suitable location, whereby automatic control of the effective cooling area of the evaporator between 100% and 0% capacity may be secured.

Other objects and advantages will become apparent upon reference to the specification claims and appended drawings wherein like reference characters represent like parts in the various views and wherein

Figure 1 is a view showing one form of control system embodying this invention, many of the parts being shown in cross-section and the control system being applied to an evaporator for use in an air conditioning system.

Figure 2 is a view showing an electric motor drive for the control valve of Figure 1.

Figure 3 is a view similar to Figure 2 but showing a pneumatic operator for the control valve of Figure 1, and

Figures 4 and 5 are schematic views showing modifications of the control arrangement of Figure 1.

Referring now to Figure 1, the invention is illustrated as being applied to an evaporator 10 of a unit air conditioner 11 although it will be obvious that the principles of the invention are not limited to this particular application. The air conditioner 11 includes a casing 12 having fresh air inlet 13 and return air inlet 14 located adjacent the bottom portion thereof, a fan 15 being provided for drawing air through the air conditioner 11 by way of the inlets 13 and 14 and discharging the air into the space to be conditioned by way of the exhaust outlet 16. A damper 17 is provided for controlling the relative amounts of fresh and return air admitted to the air conditioner, this damper being either manually controlled or controlled automatically by any suitable means. Located in the path of air from the inlets 13 and 14 to the fan 15 is the evaporator 10 of a refrigeration system, the

air in passing over this evaporator having its temperature reduced thereby.

The refrigeration system includes a compressor 20 driven by a motor 21, the high pressure side of the compressor being connected by means of a pipe 22 to the condenser 23, the outlet of the condenser being connected by means of pipes 24 and 25 to the inlet of a thermostatic expansion valve 26 which may be of any conventional construction, the low pressure side of which valve communicates by means of pipe 27 with the inlet of the evaporator 10. The outlet of the evaporator communicates by means of the pipe 28 with the inlet of the compressor 20.

The thermostatic expansion valve 26 may be of any suitable construction and is shown to comprise a valve element 30 cooperating with a valve seat 31, the valve element 30 being connected by means of the stem 32 with an operating diaphragm 33. The valve stem 32 may carry a suitable spring retainer 35 against which the compression spring 36 acts to bias the valve element towards closed position. Suitable packing 37 may be provided around the valve stem 32 to reduce leakage of refrigerant thereby. The diaphragm 33 has a chamber formed above the same by means of the cover member 38 and this space above the diaphragm is connected by means of the capillary tube 39 to the bulb 40, which tube and bulb may be provided with a suitable volatile fill so that variations in temperature to which the bulb 40 responds will cause varying pressures to act downwardly on the diaphragm 33. The bulb 40 is positioned in intimate engagement with the outlet portion of the evaporator 10 so that the pressure applied to the upper side of the diaphragm 33 will vary in accordance with variations in temperature of the refrigerant leaving the evaporator 10. The pressure in the space below the diaphragm 33 may be that of the refrigerant adjacent the outlet portion of the evaporator or some higher pressure depending upon the setting of the control device to be hereinafter explained.

This control device is illustrated generally by the reference character 42 and comprises a valve assembly 43 and an operating mechanism 44 which is shown to be mounted by means of a mounting bracket 45 on a suitable panel board 46. The valve assembly 43 comprises a valve casing 48 into the lower portion of which is removably secured a valve seat 49 with which cooperates the valve element 50 carried by the rod 51 extending upwardly through the valve body and being guided by means of the member 52 which is screw-threadedly received into the upper portion of the valve body and is held against the lower wall of the casing of the operating mechanism 44 by means of a nut 53. A suitable washer 54 may be provided between the valve body 48 and the member 52 to prevent leakage of refrigerant between these members from the interior of the valve body 48. A sealing bellows 56 is suitably secured to the upper portion of the member 52 and to the upper end of the valve stem 51 to prevent leakage of refrigerant from the interior of the valve body by way of the member 52.

Screw-threadedly received by the lower end of the valve body 48 is a fitting 60 having an inlet 61 communicating by means of the passage 62 with the underside of the valve element 50. The lower end of this fitting 60 has a member 64 threaded into the lower portion thereof, which member is provided with a suitable inlet opening 65 which communicates by way of the passage 66 and an orifice 67 with the passageway 62. The orifice

67 may be screw-threaded into the fitting 60 as illustrated so that an orifice of any desired size may be inserted therein. Suitably held between the member 64 and the fitting 60 is a strainer 70 which, as shown, is readily movable for purposes of cleaning and prevents any dirt particles from entering the orifice 67 which might tend to clog the same.

The inlet 61 of the valve assembly 43 is connected by means of the pipe 72 with the space below the diaphragm 33 of the thermostatic expansion valve and the inlet 65 is connected by means of the pipes 73 and 25 with the high pressure side of the expansion valve. The outlet 75 of the valve assembly 43 is connected by means of a pipe 76 and the pipe 77 to the outlet portion of the evaporator 10, there also being a connection 78 between the pipe 76 and a portion of the evaporator 10 spaced somewhat from the outlet of the evaporator, the connection through the pipes 77 and 78 being under the control of a manually operated three-way valve 80 for a purpose to be later described.

Located in the return air inlet 14 is a bulb 81 connected by means of a capillary tube 82 with a bellows 83 which is suitably secured to the lower portion of the casing 44, this tube, bulb and bellows being provided with a suitable volatile fill whereby the bellows 83 will expand or contract in accordance with variations in the return air temperature. While the bulb 81 is illustrated as being located in the return air duct, it should be understood that if desired this bulb may be located any place within the space being conditioned. Suitably connected to the bellows 83 is a plunger 84 for controlling the position of a lever 85 pivoted about the knife edge 86 which may be carried by the bracket 87, the right-hand end of this lever having a bearing member 88 which bears against the upper end of the valve stem 51. The left end of the member 85 moves between stops 90 and 91 which may be carried by the side wall of the casing 44 and which serve to limit the movement of the lever 85 about the pivot 86. The right end of the lever 85 is biased upwardly by means of the tension spring 92 having one end connected to the upturned end 93 of the lever 85 and the other end looped through the adjustable bracket member 95. It will be apparent from the description thus far that as the temperature of the space or in other words, the temperature of the air entering the return air duct increases, the bellows 83 will expand moving the plunger 84 upwardly which will cause movement of the lever 85 about the pivot 86 in opposition to the spring 92 so as to urge the valve stem 51 downwardly to move the valve element 50 away from the seat 49, and upon a decrease in the space temperature the reverse action will take place.

The spring 96 is a compensating spring for a purpose to be more fully explained and this spring is shown to be adjustably connected by means of a nut 97 to the adjusting bolt 98 held in the top of the casing 44. The lower end of this spring 96 is looped through the upturned end 100 of a lever 101 pivoted at 102 by means of the knife edge 103 forming an extremity of the member 104 suitably fixed to the inner side wall of the casing 44. Adjacent the connection between the spring 96 and the lever 101 is a thrust member 105 which terminates in suitable knife edges and rests in the depression 106 in the lever 101 and the depression 107 formed in the bracket 108 suitably secured to the lever 85.

When the valve 50 is in the closed position as illustrated, the pivot points of the member 105 are in direct alignment with the pivot of the lever 85 at the knife edge 86 so that the force exerted by the spring 96 in biasing the lever 101 upwardly can have no tilting effect whatever upon the main operating lever 85.

When, however, the temperature in the space increases and the bellows 83 expands, moving the lever 85 in a direction to move the valve element 50 downwardly away from the seat 49, the upper end of the thrust member 105 will be carried to the left by reason of the movement of the bracket 108 carried by the lever 85, so that the pivot points of the member 105 are no longer in line with the knife edge pivot 86 and the force of the spring 96 is now effective to assist the bellows 83 in moving the left end of the lever 85 upwardly. The further that the left end of the lever 85 is moved upwardly, the further the upper end of the member 105 will be moved toward the left so as to increase the effective moment arm of the spring 96 so that this will exert a continuously increasing force on the lever 85 in opposition to the biasing effect of the spring 92. The sealing bellows 56 will have a certain spring rate so as this bellows is gradually compressed a gradually increasing force is required to further compress the same. The spring 96 by reason of the action aforescribed is thus effective in compensating for the spring rate of the bellows 56. As the valve 50 opens, a gradually increasing refrigerant pressure will be applied to the interior of the bellows 56, and the spring 96 is effective in compensating for this increasing resistance to the opening movement of the valve. The spring 92 which biases the right end of the lever 85 upwardly is preferably a relatively stiff spring so that a slight movement of the supporting member 95 will be effective in causing a substantial adjustment of the control range of the operating mechanism 44. However, if the spring 96 were not employed it would require a very substantial temperature change at the bulb 81 to cause the movement of the valve 50 between open and closed positions so that the operating differential of the apparatus would be very high. It is desirable however that this operating differential be relatively low such as 2° or 2½° F., and since the spring 96 assists in the opening movement of the valve element 50, a relatively strong spring 92 may be employed so that adjustment of the control point of the apparatus may be effected by a slight change in position of the supporting bracket 95 while at the same time maintaining the operating differential of the device at a relatively low value. Obviously, this differential may be adjusted by means of the adjusting screw 98 by varying the position of the upper end of the spring 96 and therefore the force exerted by this spring. If the spring 96 is tensioned sufficiently, the valve 50 may be operated as a two-position or snap acting valve.

The member 95 which supports the upper end of the spring 92 may be substantially U-shaped in cross-section, the depth of the U progressively decreasing from the left end to the right, as illustrated, the side walls of the member 95 at the left end thereof being suitably recessed at 110 and carried by these recesses is a member 111 terminating in a knife edge 112 which knife edge portion fits into the V slot 113 of the member 104. This knife edge forms a pivotal support for the member 95. An adjusting screw 115 journalled in the panel board 46 has affixed to its

outer end an operating knob 116 which may carry a pointer 117 for cooperation with suitable indicia which may be suitably mounted on the front of the panel board 46. The inner end of the screw 115 has threadedly mounted thereon a nut 120 which is carried between the side walls of the member 95 and is prevented from rotation thereby. The member 95 at its left end has inturned portions 121 which may loosely straddle the bolt 115 and which bear against the nut 120 by reason of the biasing effect exerted on the member 95 by the spring 92. If the knob 116 is turned in a direction so as to move the nut 120 toward the left, the member 95 will pivot upwardly about the knife edge pivot 112 which will have the effect of moving the upper portion of the spring 92 upwardly to increase the tension thereof. Conversely, upon movement of the knob 116 in the opposite direction, the nut 120 will move toward the right thus permitting the right end of the supporting member 95 to drop downwardly and reducing the force exerted by the spring 92. By reason of the long lever arm between the pivot 112 and the right end of the member 95, a large movement may be imparted thereto with a slight movement of the knob 116. This knob 116 and the mechanism operated thereby forms an adjusting means whereby the temperature setting of the operating mechanism 42 may be adjusted. Thus upon an increase in the tension of the spring 92 a greater force will be required of the bellows 83 to move the valve element 50 downwardly so that in this manner the temperature setting of the device is increased.

Also journalled in the panel board 46 is a shaft 125 carrying a pair of cams 126 and 127 for controlling the positions of mercury switches 128 and 129, respectively. The position of the shaft 125 may be controlled by a knob 130 on the front of the panel board and similar to the knob 117. The cams are so arranged that as they are moved in a counter-clockwise direction, the switch 129 will first move to open position and upon further movement in the same direction the switch 128 will move to open position. The switch 128 controls the operation of the fan 15, the circuit to this fan being as follows: from the line wire L1 through conductor 132, switch 128, conductor 133, the fan motor 15, and conductor 135 to the line wire L2. The switch 129 controls the circuit to the compressor motor 21, this circuit being as follows: from the line wire L1 through conductor 136, switch 129, conductor 137, control device 138, conductor 139, compressor motor 21 and conductor 140 to the line wire L2. Accordingly, when the two mercury switches are in the positions illustrated the fan 15 will be operating and the compressor 20 will operate under the control of the control device 138 to be described. If the knob 130 is rotated so as to open the circuit through the switch 129, the fan 15 only will operate, since the circuit to the compressor motor has been interrupted. If both switches are opened, the entire system will of course shut down.

The control device 138 may be of any suitable construction and may comprise a high pressure switch connected to the high pressure line 22 of the refrigeration system by means of the pipe 145 and a low pressure switch connected by means of the pipe 146 to the suction line 28. These switches may be connected in series so that when either the high pressure exceeds a desired value or the suction pressure drops below a desired value the compressor will be shut

down. This control also may be of the type shown and described in application Serial No. 196,447, filed March 17, 1938, by A. L. Judson and C. G. Kronmiller, now Patent No. 2,244,783, issued June 10, 1941, which type of control arrangement insures automatic defrosting of the evaporator after each operating cycle of the compressor. Since the details of this control apparatus form no part of the present invention, they have not been illustrated.

The operation of the system shown in Figure 1 is as follows: with the switch 130 in the position illustrated the fan 15 in the air conditioner unit 11 is operating and the compressor 20 is under the control of the controller 138. With the parts in the positions illustrated, it is assumed that the temperature of the air in the space, or the air entering the return air duct is at a sufficiently low value so that the bellows 83 is contracted and the lever 85 is in the position illustrated whereby the valve 50 is maintained in closed position by reason of the spring effect of the bellows 56 and also by reason of the pressure of the refrigerant which leaks into the bellows around the valve stem 51. If necessary, a spring can be positioned within the bellows 56 to insure that the valve element 50 will remain in closed position at this time although under normal conditions such a spring is unnecessary. With the valve element 50 closed, the connection between the evaporator outlet and the space below the diaphragm 33 of the expansion valve is shut off and the liquid refrigerant from the high pressure side of the valve which passes into the space below the diaphragm 33 by way of the orifice 61 will cause a pressure to build up below this diaphragm which will be sufficient to maintain the expansion valve in tightly closed position. Since there is leakage between the space below the diaphragm 33 and the pipe 27 leading to the evaporator, the pressure below the diaphragm will not build up to an excessive amount so that danger of rupture of the diaphragm is prevented. With the expansion valve held in its tightly closed position at this time, no refrigerant will pass into the evaporator with the exception of that small amount which passes thereto around the stem of the expansion valve and accordingly the compressor will very quickly shut down since the suction pressure switch will open almost immediately after the expansion valve has been tightly closed. If desired, a separate switch might be placed in the compressor circuit, this switch being arranged to open when the valve element 50 moves to closed position, so as to shut the compressor down at this time and prevent any re-cycling thereof as long as valve 50 is closed.

If now the temperature in the space starts to increase, expansion of the bellows 83 will take place which will result in movement of the lever 85 in a direction to start opening the valve member 50 and provide communication between the outlet portion of the evaporator 10 and the space below the diaphragm 33 of the expansion valve. As this valve starts to open the pressure below the diaphragm 33 will decrease and the expansion valve will then be under the control of the bulb 40 positioned at the outlet of the evaporator and of the pressure of the refrigerant which pressure will depend upon the extent of opening of the valve member 50, among other things.

Thus if the temperature of the space has risen sufficiently so that the valve member 50 is wide open, the pressure below the diaphragm 33 will be substantially that of the refrigerant at the

evaporator outlet because at this time the leakage of liquid refrigerant into the space below the diaphragm and of the refrigerant around the stem of the expansion valve will be negligible, because of the small size of the passageways between the liquid line and the space below the diaphragm and around the expansion valve stem, as compared to the passageway through the pipes 76 and 77. Accordingly, with the valve 50 wide open, the expansion valve will respond to the temperature of the refrigerant leaving the evaporator and to the pressure of the refrigerant leaving the evaporator, or in other words, to the superheat of the refrigerant leaving the evaporator. As the valve 50 gradually moves towards closed position in response to a drop in the space temperature the pressure below the diaphragm 33 will be some pressure intermediate the pressure at the evaporator outlet and the liquid line pressure depending upon how widely open the valve 50 is. As the pressure below the diaphragm increases due to the closing movement of the valve 50, it will require a higher temperature of the refrigerant leaving the evaporator in order to open the expansion valve with the result that an increasingly greater portion thereof will contain superheated refrigerant as the valve 50 is moved towards closed position, until when entirely closed the expansion valve will entirely cut off the flow of refrigerant through the evaporator since the temperature at the bulb 40 will not normally rise high enough to cause opening movement of the expansion valve at this time. Thus as the space temperature increases, the expansion valve is operated in such a manner that a lesser portion of the evaporator contains superheated refrigerant so that the effective cooling surface of the evaporator will increase as the space temperature increases and conversely will decrease in accordance with the decrease in the space temperature and in this manner 100% modulation of the evaporator coil is secured. The valve 50 may be so characterized as to produce straight line modulation of the effective cooling area of the evaporator. As stated previously, the differential of the control apparatus 42 will preferably be in the neighborhood of 2° or 2½; so that if the space temperature is 75°, for example, the expansion valve may be entirely closed and at 77° it may be operated in accordance with the superheat of the refrigerant leaving the evaporator so that the entire surface thereof is available for cooling and intermediate these temperatures a smaller portion of the evaporator will contain liquid refrigerant depending upon the space temperature. By manipulation of the adjusting knob 116 the actual temperature which is maintained by the apparatus may be effectively controlled as previously described.

In some cases it may be that sufficient liquid refrigerant will flow through the connection 76 and 77 when the valve member 50 is open so that all of this liquid refrigerant will not be evaporated and may pass to the compressor. In such a case it will be desirable to connect the pipe 76 to the evaporator by way of the connection 78 so that there will be sufficient opportunity for this liquid refrigerant to evaporate in the evaporator and in such a case the valve 88 will be manipulated to make the connection between the pipe 76 and the evaporator at the point 78 which will still be preferably adjacent the outlet portion of the evaporator but far enough removed therefrom to insure the evaporation of the small amount of liquid refrigerant that will pass there-

to by way of the pipe 73 and the orifice 67. If a distributor is provided between the evaporator and the expansion valve, the connection 78 might be made adjacent the low pressure side of the distributor.

Referring now to Figure 2, the details of an electric motor mounting to be attached to the valve 43 in place of the self contained power unit of Figure 1 are illustrated. In place of the nut 63 at the upper portion of the valve assembly 43, a fitting 160 which encloses the bellows 56 is screw-threadedly secured to the upper portion of the valve assembly and clamps between it and the valve assembly, a bracket member 161 to which may be suitably secured as by the ears 162 and bolts 163, a motor 164 which motor may be a proportioning motor of the type illustrated in Patent No. 2,028,110, issued to D. G. Taylor on January 14, 1936. This motor may include a shaft 165 passing through an opening 166 in the bracket member 161, this shaft carrying adjacent its outer end a cam 167 which acts upon an adjustable screw 168 threaded into a member 169 which is adapted to slide within the opening 170 in the upper portion of the fitting 160. To prevent rotation of the member 169, it may be slotted as at 171 and a bolt 172 threaded through the side of the fitting 160 may pass into the slot 171 so as to permit vertical reciprocation of the member 169 but to prevent rotation thereof. By adjusting the screw 168 in the member 169 the position of the valve member may be suitably adjusted for any position of the cam 167. It will now be apparent that the same valve assembly 43 shown in Figure 1 is readily adaptable for use with an electric motor drive without any alteration of the valve assembly itself and it will be understood that the driving motor 164 may be operated by a control potentiometer as disclosed in the aforementioned Taylor patent, which control potentiometer may be controlled by space temperature, or if desired, by space relative humidity or both.

Referring now to Figure 3 the valve assembly 43 is shown connected to a pneumatic motor for controlling the position of the same. A fitting 175 is provided in place of the fitting 160 and the upper portion of this fitting has a peripheral groove 176 for receiving a set screw 177 screw-threaded in the collar 178, which collar is connected by means of arms 179 to a bellows housing 180. Located within the housing 180 is a bellows 181 of any suitable construction and this bellows controls the position of a thrust member 182 in a manner well known in the art and which thrust member passes downwardly through an opening 183 in the top of the fitting 175 and abuts the upper end of the operating bellows 56 of the valve 43. A bridge member 185 rests on the collar 178 and supports a compression spring 186, the upper end of which is in engagement with a collar 187 of the bellows assembly for biasing the bellows to collapsed position and for biasing the thrust member 182 upwardly. A pipe 190 connects to the interior of the bellows 181 and this pipe may be connected into a pneumatic control system in a manner well known in the art, in such a manner that as the temperature of the space increases the pressure within the bellows 181 will increase whereupon the thrust member 182 will be moved downwardly to open the valve member 56 of the valve assembly 43 so that a greater portion of the evaporator is effective for cooling purposes as fully set forth above.

It will now be seen that the valve assembly 43 is readily adaptable for use with a self contained

power unit as in Figure 1, with an electric motor drive as in Figure 2 or a pneumatic motor drive as in Figure 3 without making any changes whatever in the valve assembly itself. While these figures illustrate preferred arrangements for connecting the valve to the various power units it should be understood that they are susceptible of many modifications.

Referring now to Figure 4, a modification of the system shown in Figure 1 is illustrated. In this figure the valve assembly 43 controls the flow of refrigerant through the pipe 76 to the evaporator 10 as in Figure 1 so that when the valve element 56 of the valve assembly 43 is entirely open, the pressure below the operating diaphragm of the expansion valve will be that of the refrigerant leaving the evaporator. Positioned in the pipe 73 which connects the high pressure side of the expansion valve to the opening 66 of the valve 43 is a valve 200 which may be electrically or otherwise controlled such as by a solenoid 201, the arrangement being such that when the solenoid is deenergized the valve 200 is in closed position but upon energization of the solenoid the valve moves to open position.

The valve 43 is shown to be operated in this figure by means of a proportioning motor 202 which may be of the construction shown in the aforementioned Taylor patent and which in actual practice may be mounted on the valve assembly in the manner described in connection with Figure 2. This motor is shown to be controlled by a thermostat 203 responding to the temperature of the space being conditioned and which thermostat may be of any suitable construction and may comprise a bimetallic element 206 controlling the position of an arm 204 with respect to a resistance 208, the arm 204 and the resistance 208 forming the control potentiometer for the motor 202. With the thermostat in the position illustrated it is assumed that the room temperature is excessive and the motor 202 maintains the valve 43 in open position by means of the cam 210 operated by the motor. At this time the expansion valve operates in accordance with the superheat of the refrigerant leaving the evaporator. If the space temperature starts to fall, the motor 202 will cause rotation of the cam 210 and the valve 43 will operate to cut down the flow through the pipe 76 so that at this time the diaphragm will not respond to the pressure at the evaporator outlet but to some pressure intermediate this pressure and the pressure in the inlet of the evaporator. It should be understood at this time that, as in Figure 1, there will be a certain amount of leakage from the low pressure side of the expansion valve to the underside of the operating diaphragm of the valve by way of the valve stem 32, so that while this leakage has substantially no effect when the passageway 76 is entirely unrestricted, it will have an increasingly greater effect as the flow through the passage 76 is gradually reduced. It should also be understood that at this time the valve 200 is entirely closed so that there is no communication between the liquid line 73 and the underside of the operating diaphragm and accordingly the pressure exerted on the diaphragm will be some pressure between that existing at the inlet of the evaporator and at the outlet of the evaporator depending upon the adjustment of valve 43 which in turn depends upon the temperature in the space.

Mounted on the shaft of the motor 202 is a second cam 215 which controls the position of a

mercury switch 216 and this cam is arranged to move the switch 216 to closed position whenever the motor 202 has operated the valve 43 to entirely close the passage 76. Accordingly, when the valve 43 has closed entirely and the switch 216 is simultaneously closed the solenoid 201 will be energized as follows: from the line wire 220, through switch 216, conductor 221, solenoid 201 and line wire 222. With the solenoid 201 energized at this time which, it will be understood, will take place only when the space temperature has dropped to a desired value, the valve 200 is opened and accordingly high pressure refrigerant flows to the underside of the operating diaphragm 33 of the expansion valve by way of the orifice 67 of the valve assembly 43, and as described in connection with Figure 1 this flow of high pressure refrigerant at a time when the flow of refrigerant through the connection 76 is interrupted will have the effect of causing the expansion valve to move to closed position and thus give a positive shut-off of the flow of refrigerant through the evaporator. This system operates in a manner similar to that of Figure 1 with the exception that high pressure refrigerant flows to the underside of the operating diaphragm only when positive shut-off is desired and during the remaining time the difference between the inlet and outlet pressure of the refrigerant in the evaporator is made use of to secure proper modulation.

Referring now to Figure 5, the valve assembly 43 is shown as controlling the flow of liquid refrigerant through the pipe 73 to the underside of the operating diaphragm of the expansion valve by way of pipes 240 and 241. The connection between the underside of the operating diaphragm and the evaporator outlet is provided with a suitable restricting means 243 which is illustrated as being adjustable, the adjustment of the orifice of the member 243 being effected by the screw member 244. The valve assembly 43 is again illustrated as being operated by an electric proportioning motor as shown in Figure 2 although it should be understood that any suitable operating means for the valve may be utilized. This proportioning motor is controlled by the thermostat 205 as in Figure 4 and controls the position of the cam 242 for in turn controlling the adjustment of the valve 43. A plug 245 may be provided to close the inlet 61 of the valve assembly since this inlet is not used in this form of the invention.

The arrangement is such that when the space temperature is excessive, as illustrated, the valve 43 will be in closed position thus preventing flow of high pressure refrigerant to the underside of the operating diaphragm of the valve 26 by way of pipes 73, 240, and 241 so that this diaphragm will respond to the outlet pressure in the evaporator by way of pipe 76, restriction 243, and pipe 241. As the space temperature starts to fall, the cam 242 will rotate to start opening the valve 43 thus permitting some liquid refrigerant to flow to the underside of the diaphragm of the expansion valve which thus increases the pressure so that a higher temperature at the bulb 40 is necessary to open the expansion valve and in this manner the evaporator will contain more and more superheated refrigerant as the space temperature falls so that a smaller portion thereof is effective for cooling purposes. When the space temperature has dropped sufficiently, the valve 43 will be wide open so that a sufficient amount of liquid refrigerant will flow

5 to the space below the expansion valve operating diaphragm to maintain the valve tightly closed. It will be apparent that this system is similar in operation to that of Figure 1 but that the valve 43 controls the flow of the high pressure refrigerant instead of the low pressure refrigerant to the underside of the diaphragm of the expansion valve.

10 In many installations the pressure drop through the evaporator may be so small that the provision of a connection between the diaphragm of the expansion valve and the outlet of the evaporator coil is entirely unnecessary. In such a case the pipe 76 may be entirely eliminated or the orifice 243 may be adjusted to positively close off the flow through this pipe. In such a case with the valve 43 closed, the operating diaphragm of the valve 26 will respond to the pressure at the inlet of the evaporator which, as stated, may be substantially the same as that of the outlet pressure and accordingly the expansion valve will operate in accordance with the superheat of the refrigerant leaving the evaporator to maintain the coil in a substantially flooded condition. The connection 76 however is desirable in installations where the pressure drop through the evaporator is of a considerable value and it is desirable to eliminate this only when the pressure drop is relatively insignificant.

15 20 25 30 35 40 45 50 55 60 65 70 75 In the various systems described it has been assumed that there is sufficient leakage around the stem of the expansion valve to insure that the operating diaphragm thereof will be subjected to the low pressure refrigerant at the inlet of the evaporator. Should an expansion valve be utilized that does not have a sufficient leakage around the valve stem then such a passageway may be provided, which may be an external passageway or a suitable passageway provided in the valve body. This connection between the low pressure side of the valve and the operating diaphragm is of importance since it prevents the pressure below the diaphragm due to the flow of liquid refrigerant thereto from the high pressure side of the system from becoming sufficiently great to rupture the operating diaphragm. In the various systems disclosed, the connection between the outlet of the valve 43 might be made between the expansion valve and the distributor, if a distribution be employed.

Having described some preferred embodiments of my invention, many modifications will become apparent to those skilled in the art and it should therefore be understood that the invention is limited only by the scope of the appended claims.

I claim as my invention:

1. In a refrigeration system, an evaporator means, means for circulating refrigerant through said evaporator means, thermostatic expansion valve means for controlling the flow of refrigerant through said evaporator means, said expansion valve means including a pressure responsive operating means, means providing communication between one side of said operating means and a portion of the evaporator means wherein the pressure is lower than at the inlet side thereof and means providing restricted communication between said one side of said operating means and the inlet of the evaporator means, valve means controlling the effectiveness of the communication between the operating means and the outlet portion of the evaporator means, and means forming a restricted passageway between the high pressure side of the expansion valve means and said one side of said operating means.

2. In a refrigeration system, an evaporator means, means for circulating refrigerant through said evaporator means, thermostatic expansion valve means for controlling the flow of refrigerant through said evaporator means, said expansion valve means including a pressure responsive operating means, means providing communication between one side of said operating means and a portion of the evaporator means wherein the pressure is lower than at the inlet side thereof and means providing restricted communication between said one side of said operating means and the inlet of the evaporator means, valve means controlling the effectiveness of the communication between the operating means and the outlet portion of the evaporator means, means responsive to a condition being controlled by said evaporator means in control of said valve means, and means forming a restricted passageway between the high pressure side of the expansion valve means and said one side of said operating means.

3. In a refrigeration system, an evaporator means, means for circulating refrigerant through said evaporator means, thermostatic expansion valve means for controlling the flow of refrigerant through said evaporator means, said expansion valve means including a pressure responsive operating means, means providing communication between one side of said operating means and a portion of the evaporator means wherein the pressure is lower than at the inlet side thereof and means providing restricted communication between said one side of said operating means and the inlet of the evaporator means, valve means controlling the effectiveness of the communication between the operating means and the outlet portion of the evaporator means, means responsive to the temperature of the medium being cooled by said evaporator means for operating said valve means to reduce the effectiveness of the communication between said operating means and the outlet portion of the evaporator means as the temperature of the medium decreases, and means forming a restricted passageway between the high pressure side of the expansion valve means and said one side of said operating means.

4. In a refrigeration system, an evaporator means, means for circulating refrigerant through said evaporator means, thermostatic expansion valve means for controlling the flow of refrigerant through said evaporator means, said expansion valve means including a pressure responsive operating means, means providing communication between one side of said operating means and a portion of said evaporator means wherein the pressure is lower than at the inlet side thereof, means providing communication between said one side of said operating means and the high pressure side of said expansion valve means, one of said last named means being arranged to provide for only a restricted flow therethrough, and valve means controlling the flow through the other of said last named means, and means forming a restricted passageway between said one side of said operating means and the low pressure side of said expansion valve means.

5. In a refrigeration system, an evaporator means, means for circulating refrigerant through said evaporator means, thermostatic expansion valve means for controlling the flow of refrigerant through said evaporator means, said expansion valve means including a pressure responsive operating means, means providing communication between one side of said operating means and a

portion of said evaporator means wherein the pressure is lower than at the inlet side thereof, means providing communication between said one side of said operating means and the high pressure side of said expansion valve means, one of said last named means being arranged to provide for only a restricted flow therethrough, valve means controlling the flow through the other of said last named means, means responsive to a condition being controlled by said evaporator means in control of said valve means, and means forming a restricted passageway between said one side of said operating means and the low pressure side of said expansion valve means.

6. In a refrigeration system, an evaporator means, means for circulating refrigerant through said evaporator means, thermostatic expansion valve means for controlling the flow of refrigerant through said evaporator means, said expansion valve means including a pressure responsive operating means, means forming a passageway between one side of said operating means and a portion of said evaporator means wherein the pressure is lower than at the inlet side thereof, means forming a passageway between said one side of said operating means and the high pressure side of said expansion valve means, a restriction in said first passageway for permitting only a limited flow therethrough, a valve in said second passageway for controlling the flow therethrough, and a restricted passageway between said one side of said operating means and the low pressure side of said expansion valve means.

7. In a refrigeration system, an evaporator means, means for circulating refrigerant through said evaporator means, thermostatic expansion valve means for controlling the flow of refrigerant through said evaporator means, said expansion valve means including a pressure responsive operating means, means forming a passageway between one side of said operating means and a portion of said evaporator means wherein the pressure is lower than at the inlet side thereof, means forming a passageway between said one side of said operating means and the high pressure side of said expansion valve means, a valve in said first passageway for controlling the flow therethrough, a restriction in said second passageway for permitting only a limited flow therethrough, a restricted passageway between said one side of said operating means and the low pressure side of said expansion valve means, and means responsive to a drop in temperature of the medium being cooled by said evaporator means for moving the valve in said first passageway towards closed position.

8. In a refrigeration system, an evaporator means, means for circulating refrigerant through said evaporator means, thermostatic expansion valve means for controlling the flow of refrigerant through said evaporator means, said expansion valve means including a pressure responsive operating means, means forming a passageway between one side of said operating means and a portion of said evaporator means wherein the pressure is lower than at the inlet side thereof, means forming a passageway between said one side of said operating means and the high pressure side of said expansion valve means, a restriction in said first passageway for permitting only a limited flow therethrough, a valve in said second passageway for controlling the flow therethrough, a restricted passageway between said one side of said operating means and the low pressure side of said expansion valve means, and means

responsive to a drop in temperature of the medium being cooled by said evaporator means for moving the valve in said second passageway towards open position.

9. In a refrigeration system, an evaporator means, means for circulating refrigerant through said evaporator means, thermostatic expansion valve means for controlling the flow of refrigerant through said evaporator means, said expansion valve means including a pressure responsive operating means, means forming a passageway between one side of said operating means and a portion of said evaporator means wherein the pressure is lower than at the inlet side thereof, means forming a passageway between said one side of said operating means and the high pressure side of said expansion valve means, valve means in each of said passageways, and means for opening the valve means in the second of said passageways only when the valve means in the first of said passageways has moved to closed position, and a restricted passageway between said one side of said operating means and the low pressure side of said expansion valve means.

10. In a refrigeration system, an evaporator means, means for circulating refrigerant through said evaporator means, thermostatic expansion valve means for controlling the flow of refrigerant through said evaporator means, said expansion valve means including a pressure responsive operating means, means forming a passageway between one side of said operating means and a portion of said evaporator means wherein the pressure is lower than at the inlet side thereof, means forming a passageway between said one side of said operating means and the high pressure side of said expansion valve means, valve means in each of said passageways, means for opening the valve means in the second of said passageways only when the valve means in the first of said passageways has moved to closed position, and a restricted passageway between said one side of said operating means and the low pressure side of said expansion valve means, and means responsive to the temperature of the medium being cooled by said evaporator means for moving the valve means in the first of said passageways towards closed position as the temperature of the medium falls.

11. In a refrigeration system, an evaporator means, means for circulating refrigerant through said evaporator means, thermostatic expansion valve means for controlling the flow of refrigerant through said evaporator means, said expansion valve means including pressure responsive means, means subjecting said pressure responsive means to a pressure corresponding to the temperature of the refrigerant in the evaporator means for urging said pressure responsive means in one direction, means forming a pressure chamber wherein the pressure urges said pressure responsive means in the opposite direction, means providing communication between said chamber and a part of said evaporator means wherein the pressure is lower than at the inlet thereof, means providing communication between said chamber and the high pressure side of said expansion valve means, one of said communication means being arranged to provide restricted flow therethrough, valve means controlling the flow through the other of said communication means, and means providing restricted communication between said chamber and the inlet of the evaporator.

12. In a refrigeration system; in combination; evaporator means; compressor means for supplying refrigerant thereto and withdrawing it therefrom; a thermostatic expansion valve in control of the flow of refrigerant to the evaporator means and including pressure responsive means operative to move said valve in opening direction with a force corresponding to the temperature of the refrigerant leaving the evaporator; means interconnecting said pressure responsive means with the evaporator means at a point remote from its inlet end and with the high pressure side of said system ahead of said expansion valve in such a manner that said pressures act in a direction to close said expansion valve; means, including restricting means and valve means actuated by a psychometric condition of the air being cooled by said evaporator means, for varying the effect of said last named pressures from a value equal to the pressure in the evaporator means at said point of connection to a higher value sufficient to reduce the capacity of said evaporator means by at least thirty percent as the value of said condition changes in a given direction, and to apply high side pressure to said pressure responsive means to positively close said expansion valve when the value of said condition deviates to a predetermined value in the same direction; and means to relieve the high side pressure applied to said pressure responsive means sufficiently to prevent damage thereto while maintaining said pressure high enough to maintain said expansion valve closed.

13. In a refrigeration system, in combination, evaporator means, means for supplying refrigerant thereto including a relatively high pressure source of refrigerant, valve means in control of the flow of refrigerant from said source to said evaporator means and including a pressure responsive means, means interconnecting said pressure responsive means with the inlet side of said evaporator means and with a point in said evaporator means remote from said inlet side, means including valve means associated with at least a portion of said connections to determine the pressure applied to said pressure responsive means, a further connection between said pressure responsive means and said high pressure source, and means including valve means for controlling the application of said high pressure to said pressure responsive means.

14. In a refrigeration system, in combination, evaporator means, means for supplying refrigerant thereto including a relatively high pressure source of refrigerant, valve means in control of the flow of refrigerant from said source to said evaporator means and including a pressure responsive means, means interconnecting said pressure responsive means with the inlet side of said evaporator means and with a point in said evaporator means remote from said inlet side, means including valve means associated with at least a portion of said connections to determine the pressure applied to said pressure responsive means, a further connection between said pressure responsive means and said high pressure source, means including valve means for controlling the application of said high pressure to said pressure responsive means, and means for operating said two last-mentioned valve means in sequence.

ALWIN B. NEWTON.
